UNITED STATES PATENT OFFICE.

JOHN G. O'DONNELL, OF WASHINGTON, DISTRICT OF COLUMBIA, ASSIGNOR OF ONE-THIRD TO CHARLES J. HELMSEN AND ONE-THIRD TO EDWARD A. HELMSEN, BOTH OF WASHINGTON, DISTRICT OF COLUMBIA.

ANTISEPTIC HOLDER FOR TELEPHONE-MOUTHPIECES.

1,112,469.

Specification of Letters Patent.

Patented Oct. 6, 1914.

Application filed August 26, 1913. Serial No. 786,711.

To all whom it may concern:

Be it known that I, JOHN G. O'DONNELL, a citizen of the United States, residing at Washington, in the District of Columbia, have invented a new and useful Improvement 5 in Antiseptic Holders for Telephone-Mouthpieces, of which the following is a specification.

This invention relates generally to telephones and more particularly to an antiseptic attachment for the mouth piece of the telephone transmitter, the object being to destroy any and all germs accumulating in the mouth piece, and thereby prevent the 5 spread of disease.

Heretofore efforts have been made to render mouth pieces antiseptic or germ proof by applying to the piece an attachment containing a pad saturated with some 0 antiseptic compound. This method is objectionable for several reasons, namely, that the liquid antiseptic very soon evaporates, and furthermore in applying this liquid 5 antiseptic it often happens too much there- of is applied and the device is therefore rendered objectionable. Devices of this kind as usually constructed contract the mouth piece instead of expanding or enlarging the same. In addition all of the 0 liquid antiseptics so far as I am aware are more or less disagreeable in odor and to be effective at all they must be constantly giving off a vapor which it is not desirable to breathe into the lungs.

The object of my invention therefore is to provide a device which will fit upon the ordinary mouth piece now in use, will not contract the entrance thereof, and will embody a powdered or granulated antiseptic which will not give off a disagreeable odor, but which will constantly emanate or throw off antiseptic or germ destroying vapors.

Another object of my invention is to provide a device embodying a solid or powdered antiseptic which will last for a considerable length of time and which can be quickly and easily replenished when necessary.

With these various objects in view my invention consists in the novel features of construction hereinafter fully described and pointed out in the claims.

In the drawings forming a part of this

specification: Figure 1 is a perspective view showing the practical application of my invention. Fig. 2 is a vertical sectional view of the same applied to the mouth piece of the telephone. Fig. 3 is a detail perspective view of the outer shell or case, and Fig. 4 is a detail perspective view of an antiseptic carrying ring.

Referring to the drawings A indicates the ordinary mouth piece of a telephone and to this mouth piece I apply the outer case or shell B of my attachment, this outer case or shell being circular in shape as shown and having a central opening through which the mouthpiece A is passed, this central opening being surrounded by oblique or tapering flange B', which snugly fits 70 upon the outer end of the mouth piece A. Within the outer shell or case B I place the annular or ring shaped carrier C, which is intended to receive the antiseptic D, this antiseptic being preferably in the form of a 75 powder and it will be noted that the inner ring of the carrier is perforated as shown at C' in order to permit the escape of the antiseptic or germ destroying vapors given off by this powdered antiseptic compound. 80 It will be noted that the inner or rear wall of the carrier ring engages the forward end of the mouth piece as shown at C² in Fig. 2 and this engaging portion is also clearly 85 illustrated in Fig. 4. After the powder has 85 been placed within the annular or ring like chamber of the carrier a ring shaped front or cover E is placed thereon to hold the powder in place and in order to hold the carrier firmly within the outer shell or case 90 and also bind all of the parts in close relation to the mouth piece A I employ a flanged fastening band F, which overlaps the forward edges of the outer case or shell and the annular carrier as most clearly shown in 95 Figs. 1 and 2 and the horizontal portion of this flanged ring is slotted as shown at F' which slot is adapted to engage a pin or boss F² carried by the outer shell or case so that after the flanged band has been applied and 100 given a slight turn the engagement of the pin or boss with the inclined slot will serve to bind all the parts tightly together holding them in their proper fixed relations.

An attachment constructed as herein shown 105 and described completely overcomes all of

the objections hereinbefore referred to and enables me to provide a carrier of sufficient size to receive and hold a considerable quantity of powdered antiseptic which will constantly give off the germ destroying vapors for a long time, said vapors being of a pleasant nature rather than of a disagreeable kind.

When it is desired to replenish the carrier 10 the locking band is removed and the carrier removed, replenished, replaced in the outer shell or case, and the ring and band applied as heretofore described.

What I claim is:

15 1. In a device of the kind described an outer shell or case adapted to be attached to the mouth piece of the telephone, a perforated carrier arranged within the outer shell or case and adapted to receive and hold a 20 powdered antiseptic, means for closing the front of said carrier together with means for

securing said carrier in the outer shell or case.

2. A device of the kind described comprising an outwardly flaring shell or case having a central opening surrounded by a tapered flange adapted to receive the outer end of the telephone mouthpiece, an annular carrier perforated upon the interior and adapted to receive a powdered antiseptic, 25 said carrier being adapted to fit within the outer shell or case and bear against the forward end of the mouth piece, the interior diameter of the carrier being co-extensive with the mouth piece, and means for securing said carrier within the outer shell or case and simultaneously connecting said parts to the mouth piece as set forth.

JOHN G. O'DONNELL.
